CLAIM

The ornamental design of a container lid, as shown and described.

DESCRIPTION

FIG. 1 is a front perspective view of a container lid according to my new design;

FIG. 2 is a top plan view of the container lid shown in FIG. 1;

FIG. 3 is a right side elevational view of the container lid shown in FIG. 1;

FIG. 4 is a bottom plan view of the container lid shown in FIG. 1;

FIG. 5 is a left side elevational view of the container lid shown in FIG. 1; and,

FIG. 6 is an enlarged rear elevational view of the container lid shown in FIG. 1.

The broken lines shown in the drawings are for illustrative purposes only and form no part of the claimed design.
